UNITED STATES PATENT OFFICE.

FORD W. HARRIS, OF LOS ANGELES, CALIFORNIA.

THREE-ASPECT SIGNAL.

Application filed January 3, 1920. Serial No. 349,312.

To all whom it may concern:

Be it known that I, FORD W. HARRIS, a citizen of the United States, residing at Los Angeles, in the county of Los Angeles, State 5 of California, have invented a new and useful Three-Aspect Signal, of which the following is a specification.

My invention relates to signals such as are used at railroad crossings for the purpose of indicating the approach of a train.

The principal object of my invention is to provide a signal which will give a clear or safety indication under normal conditions, which will give an out-of-order signal upon 5 failure of the current supply or mechanism, and which will give a danger signal whenever a train approaches the crossing.

A further object of my invention is to provide a signal of this character in which 0 a target and a mask for the target are used, the mask hiding the target to indicate that the crossing is clear and moving away to expose the target whenever the current supply fails, or whenever a train approaches 5 the crossing.

I also provide for the oscillation of the target during the time a train is approaching the crossing and I utilize this oscillation to reset the mask in the clear position.

Further objects and advantages will be made evident hereinafter.

Referring to the drawings, which are for illustrative purposes only.

Fig. 1 is a side elevation partly in section showing my signal in the clear position.

Fig. 2 is a side view of same.

Fig. 3 is a side elevation partly in section showing my signal in the out-of-order 0 position.

Fig. 4 is a side elevation partly in section showing in full lines the position assumed by the signal at one end of the stroke and in dotted lines the position assumed by the 5 signal at the other end of the stroke during the oscillation or danger indication, portions of the signal being omitted for the sake of clearness.

Fig. 5 is a diagram of connections.

Fig. 6 is an enlarged view showing the toggle links used.

In the form of the invention illustrated in these drawings a case 11 is provided, this case being supported on angle irons 12 which 5 are carried in a suitable structure. Journalled to turn freely in the case 11 is a

target shaft 13 and a mask shaft 14. Secured to the target shaft 13 is an armature 15, which is oscillated by suitable electro-responsive means such as the coils 16 and 17, these coils being energized by a switch having stationary contacts 18 and a moving contact 19 as shown in the diagram Fig. 5, the arrangement of the coils and switch being similar to that shown in the Patent to 60 Bell et al. 1,160,243, patented November 16, 1915. A target counterweight 20 is provided, secured to the target shaft 13 and a bent pipe arm 21 is also secured to this shaft projecting down and carrying a circular target 22, which may be provided with illuminating means 23 if desired. Secured to the mask shaft 14 is a pipe arm 30, which carries a square mask 31, this mask being provided with a bottom 32 and with sides 75 33, so that the target is obscured thereby when the parts are in the position shown at Fig. 1. A mask counterweight 34 is secured to the mask shaft 14. Shields 35 are secured to the angle irons 12 as shown. 80

Located inside the case 11 is the mask restraining mechanism. This includes a short mask lever arm 40 secured to the shaft 14 and a long target lever arm 41 secured to the shaft 13. Pivoted on a pin 42 in the lever arm 41 is an armature link 43, which is pivoted by a pin 44 to a magnet link 45, this magnet link 45 being in turn pivoted on a pin 46 carried in the lever arm 40. A magnet 47 is also carried on the lever arm 45, this magnet being so placed that it readily holds an armature 48, which forms an extension to the link 43. The pin 44 is slightly off center from the line connecting the pins 42 and 46 so that there is a tendency for the toggle formed by the links 43 and 45 to break in the direction of the arrow A of Fig. 6 unless restrained by the magnet 47. The diagram of connections is shown in Fig. 5, in which 50 are the insulated rails of the track of the railway upon which the crossing is located. A track battery 51 is connected at either terminal to one of the rails 50 and at either terminal to the operating coil of a relay 52, having upper contacts 53 and lower contacts 54. A movable contact member 55 engages either the contacts 53 or the contacts 54. An operating battery 56 has one terminal connected to the movable member 19 of the oscillating switch and to one terminal of the magnet 47. The contacts 18 are each con-

105

100

105

110

nected to one terminal of one of the coils 16, the other terminals of these coils being connected together and connected to one of the lower contacts 54 of the relay. One of the upper contacts of this relay is connected to the other terminal of the magnet 47. The other contacts 53 and 54 are connected to the other terminal of the operating battery.

10 The method of operation is as follows:

Under normal conditions and with no train approaching the crossing, the parts are in the position shown in Figs. 1 and 5, contact 55 being held in its upper position by the track battery 51, the magnet 47 thus being energized by the operating battery 56. With the parts in this position the square mask 31 completely covers the round target 22, the mask being painted white and the target being painted red. This serves to notify a vehicle approaching the crossing that there is no train approaching the crossing and that the signal is in operating condition. If the operating battery 56 fails or if the connection between the operating battery 56 and the magnet 47 fails, the circuit to the magnet 47 is interrupted. If the track battery 51 fails or if this battery is short-circuited by a train coming across the rails 50, the moving contact 55 of the relay 52 drops, thus opening the circuit to the magnet 47.

In any of these cases the opening of the circuit of the magnet 47 demagnetizes the core thereof and the armature 48 is released, the toggle formed by the links 43 and 45 being broken and collapsing into the position shown in Fig. 3. The counterweight 34 throws the mask into the position shown in Fig. 3 behind the shield 35 secured to the angle irons 12. At the same time the target moves slightly to the left from the position shown in Fig. 1 into the position shown at Fig. 3. This indicates that the signal is out of order in the event that the target is stationary. If however the operating battery is intact and the interruption to the coil 47 is due to the relay contact 55 dropping, there is an oscillation of the signal, due to the closing of the circuit through the oscillating mechanism by the closing of the circuit across the contacts 54. If therefore the track battery 51 has failed or the wires leading from the track battery 51 to the relay coil 52 have been broken or the battery has been short-circuited, due to the presence of a train on the insulated rails 50, there is an oscillation of the signal which will continue until the battery 56 is entirely exhausted or the relay 52 is restored to its original upper position. During this oscillation the target 22 swings through an arc indicated by the extreme positions shown in full lines and dotted lines in Fig. 4. Every time the target reaches one extreme of this

arc as indicated in full lines in Fig. 4 the links 43 and 45 are pulled into the position shown in Fig. 6 so that the magnet 47 could hold them in that position were it energized. Whenever, therefore, the coil of the relay 52 is again energized, thus pulling contact 55 into its upper position, there is a simultaneous interruption of the current supply to the oscillating mechanism together with a restoral of the current supply of the magnet 47. The parts are so arranged that there is very little friction and the target 22 will make a considerable number of swings before coming to rest after current to the coils 16 and 17 is cut off. The result is that as soon as the current is taken off the operating mechanism and the magnet 47 is energized the toggle formed by the links 43 and 45 is reset upon the next swing of the signal. With the toggle formed by the links 43 and 45 held in rigid relationship the weight of the target 22 is sufficient to pull the mask 31 downwardly from behind the shields 35 into the position shown in Fig. 1. In other words, the members move from the position shown in full lines in Fig. 4 into the position shown in Fig. 1. This is the clear or safe indication of the signal. It will be noted that this clear or safe indication is dependent not only upon the integrity of the batteries 51 and 56 and the wiring running therefrom, but that the resetting of the signal to clear position requires a perfect actuation of the signal. If for any reason the signal fails to oscillate after the mask 22 has been allowed to move behind the shields 35 or in the event that the oscillation is only partial, it is impossible for the signal to reset and it continues to hang in the position shown in Fig. 3, thus indicating danger in the sense that it indicates that the signal is out of order. In other words, it would indicate by a red target and a red light that a person approaching the crossing should use caution. If, however, for any reason the signal is in the position shown in Fig. 3, but is in operative condition at the end of any perfect operation the signal will always reset itself to clear as shown in Fig. 1.

For convenience Fig. 1 may be as a clear signal, Fig. 3 as an out-of-order or caution signal, and Fig. 4 as a danger signal.

I claim as my invention:

1. In a signal, the combination of a target member; a mask member; restraining means holding said members in such a position that said mask obscures said target; and means operable upon the release of said restraining means for moving one of said members so that said mask no longer obscures said target.

2. In a signal, the combination of a target member; means for swinging said target member; a mask member; restraining means

holding said members in such a position that said mask obscures said target; and means operable upon the release of said restraining means for moving one of said members so that said mask no longer obscures said target.

3. In a signal, the combination of a target member; a mask member; restraining means holding said members in such a position that said mask obscures said target; and means operable upon the release of said restraining means for moving said mask so that it no longer obscures said target.

4. In a signal, the combination of a target member; means for swinging said target member; a mask member; restraining means holding said members in such a position that said mask obscures said target; and means operable upon the release of said restraining means for moving said mask so that it no longer obscures said target.

5. In a signal, the combination of: a target; electrically actuated means for moving said target; a mask so mounted that it can be swung into a position to obscure said target; a weight tending to throw said mask out of its obscuring position; and members coupling said mask to said target in such relation that said mask tends to obscure said target whenever said electrically actuated means is de-energized.

6. In a signal, the combination of: a target; electrically actuated means for moving said target; a mask so mounted that it can be swung into a position to obscure said target; a weight tending to throw said mask out of its obscuring position; and electro-magnetically restrained members coupling said mask to said target in such relation that said mask tends to obscure said target whenever said electrically actuated means is de-energized.

7. A railway crossing signal, comprising controlling means actuated by the movement of a train, a movably mounted warning device, a cover adapted to be moved into and out of position for exposing said warning device to view, means regulated by said controlling means for transmitting motion to said warning device, and means also regulated by said controlling means for maintaining the cover normally in operative covering position opposite the warning device,

but adapted during the movement of the warning device to permit the cover to be continuously in position for exposing the warning device.

8. A railway crossing signal comprising controlling means actuated by the movement of a train, a movably mounted warning device, a cover adapted to be moved into and out of position for exposing said warning device to view, a motor operatively connected with said warning device for transmitting motion thereto, means for moving the cover into operative covering position with respect to the warning device, a clutch for operatively connecting said motor with said cover moving means, means regulated by said controlling means for throwing said clutch into and out of operation, and means regulated by said controlling means for starting and stopping said motor.

9. A railway crossing signal comprising controlling means actuated by the movement of a train, a movably mounted warning device, a cover adapted to be moved into and out of position for exposing said warning device to view, a motor operatively connected with said warning device for transmitting motion thereto, means for moving the cover into operative covering position with respect to the warning device, a clutch for operatively connecting said motor with said cover moving means, and means regulated by said controlling means for throwing the clutch into operation at the end of the predetermined desired period of operation of the motor.

10. A railway crossing signal comprising an electric switch regulated by the movement of a train, a swinging warning device, means for swinging said warning device, an oscillating cover adapted to be swung into and out of position covering the warning device, and means operative when the switch is in one position for causing the cover to move out of operative covering position and operative when the switch is in the other position for causing said cover to move again to its normal covering position.

In testimony whereof, I have hereunto set my hand at Los Angeles, California, this 19th day of December 1919.

FORD W. HARRIS.
